DESIGN FOR A PHONOGRAPH CABINET

David C. Rockola, Chicago, Ill.

Application October 12, 1936, Serial No. 65,264

Term of patent 3½ years

To all whom it may concern:

Be it known that I, David C. Rockola, a citizen of the Dominion of Canada and a resident of Chicago, in the county of Cook and State of Illinois, have invented a new, original, and ornamental Design for a Phonograph Cabinet, of which the following is a specification, reference being had to the accompanying drawing, forming a part thereof, and in which:

Fig. 1 is a perspective view of the phonograph cabinet showing my new design; and

Fig. 2 is a top plan view of the same.

I claim:

The ornamental design for a phonograph cabinet, as shown.

DAVID C. ROCKOLA.
